UNITED STATES PATENT OFFICE.

FRANK LEMUEL ADRIAN, OF MATTOON, ILLINOIS.

ENGINE-PISTON.

1,382,876.

Specification of Letters Patent. Patented June 28, 1921.

Application filed February 11, 1921. Serial No. 444,181.

To all whom it may concern:

Be it known that I, FRANK L. ADRIAN, a citizen of the United States, residing at Mattoon, in the county of Coles and State of Illinois, have invented a new and useful Engine-Piston, of which the following is a specification.

This invention relates to piston constructions, the object of the invention being to provide novel means for insuring against lateral wear of the piston or cylinder walls in which the piston operates, thereby eliminating what is commonly known in general practice, as piston slap.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a vertical sectional view through a cylinder showing a piston constructed in accordance with the present invention, as mounted therein;

Fig. 2 illustrates a sectional view taken on line 2—2 of Fig. 1; and

Fig. 3 illustrates a sectional view taken on line 3—3 of Fig. 1.

Referring to the drawing in detail, the reference character 5 designates a cylinder in which is mounted the piston 6, which piston is provided with the usual piston rings 7 for providing a close fit between the piston and wall of the cylinder.

Formed integral with the piston 6 and extending from the lower edge thereof, are

the depending arms 8 which have the blocks 9 secured thereto, the blocks 9 being disposed adjacent to the lower ends of the arms 8.

Secured to the inner wall of the cylinder 45 adjacent to the lower end thereof, are the spaced bars 10, the space between the bars 10 being such as to accommodate the block 9 associated therewith, thereby providing a guide for the arms 8 to eliminate any possibility of the piston moving laterally within its cylinders.

From the foregoing it is obvious that as the piston 6 moves longitudinally of its cylinder, the arms are guided in their guideways to the end that the piston is held in alinement with the wall of the cylinder at all times.

Having thus described the invention, what is claimed as new is:—

1. In a device of the character described, a cylinder having spaced bars arranged in pairs and secured to the inner wall thereof, a piston operating in the cylinder, said piston having depending arms, and means carried by the arms and disposed between the bars, for guiding the arms.

2. In a device of the character described, a cylinder, pairs of bars disposed within the cylinder, a piston operating in the cylinder, 70 arms having connection with the piston, each of said arms carrying a block, said blocks adapted to move between the bars for guiding the piston, and said bars being secured to the walls of the cylinder.

In testimony that I claim the foregoing as my own, I have hereto affixed my signature in the presence of two witnesses.

FRANK LEMUEL ADRIAN.
